[57] **CLAIM**

The ornamental design for a housing for computer data storage drive, as shown and described.

DESCRIPTION

FIG. 1 is a perspective view of a housing for computer data storage drive showing my new design;

FIG. 2 is a side elevational view thereof on an enlarged scale;

FIG. 3 is a opposite side elevational view thereof;

FIG. 4 is a bottom plan view thereof;

FIG. 5 is a rear end elevational view thereof; and,

FIG. 6 is a front end elevational view thereof.

FIG. 1

FIG. 2

FIG. 3

FIG. 4

FIG. 5

FIG. 6
